Term of patent 14 years

(Cl. D52—10)

FIG. 1

FIG. 2

FIG.3

FIG.4

FIG.5

FIG.6

FIG.7

FIG. 8

FIG. 1 is a top plan view of a bath scale, embodying my new design;

FIG. 2 is a fragmentary view of a corner portion of FIG. 1 showing more clearly all of the specific ornamental details on an enlarged scale;

FIGS. 3, 4, 5 and 6 are, respectively, back, front, right and left side elevational views of the bath scale;

FIG. 7 is a fragmentary view of a portion of the frame of the bath scale as illustrated in FIGS. 3-6, showing more clearly all of the specific ornamental details on an enlarged scale; and

FIG. 8 is a bottom plan view of the bath scale.

The dominant features of the design reside in the portions shown in full lines. It is to be understood that the surface shading within the framed border in FIG. 1 representing a conventional fabric is repeated throughout the area.

I claim:

The ornamental design for a bath scale or similar article, substantially as shown and described.
